SHEET-FEEDING MECHANISM FOR EMBOSsing-PRESSES.

1,053,566.

Specification of Letters Patent. Patented Feb. 18, 1913.

Application filed December 30, 1905. Serial No. 293,912.

To all whom it may concern:

Be it known that I, ALFRED BREDENBERG, a citizen of the United States, and a resident of Champlain, Clinton county, New York, have invented certain new and useful Improvements in Sheet-Feeding Mechanisms for Embossing-Presses, of which the following is a specification.

The invention relates to embossing presses and more particularly to devices for feeding and registering sheets in presses having a pair of flat embossing surfaces.

Objects of the invention are, to provide means for rapidly and accurately feeding such sheets to the press, registering the sheets for the impression, removing the sheets and storing them after impression; to provide sheet handling mechanism which will supply new sheets without injury to the sheets or to the embossing surfaces; to provide registering means of a simple and reliable type for positioning the sheets while carried by the sheet conveyer, and providing said mechanisms of such form and arrangement that they will perform their various functions without interference with or injury to each other. These objects of invention, together with other objects of invention, will in part be obvious and in part more fully appear hereinafter.

The invention consists in the novel parts, improvements and combinations herein shown and described.

The accompanying drawings, referred to herein and forming a part hereof, illustrate one embodiment of the invention, the same serving in connection with the description herein to explain the principles of the invention.

Of the drawings: Figure 1 is a side elevation of an embossing press; Fig. 2 is an end elevation; Fig. 3 is a detail rear elevation of the registering mechanism; and Figs. 4 and 5 are details of the gripper mechanism.

In the embodiment of the invention illustrated herewith an embossing press is shown having a pair of flat embossing members, one carrying a die and the other a counter die. As illustrated, one of said embossing members, indicated by the reference numeral 1, is mounted in a fixed relation upon a sup-

porting frame 2. The other embossing member, indicated by the reference numeral 3, is shown movable toward and from the fixed embossing member 1. The said movable embossing member 3 is provided with guiding and actuating means which may be of any suitable or convenient form, and as illustrated comprise rods 4 and side frames 4^a fixed on said rods suitably arranged and disposed for guiding the said member 3 as it moves toward and away from impression. The actuating means for the said movable embossing member 3 is shown as comprising two sets of double toggle levers 5, the said levers being actuated from a suitable source of power. In the illustrated arrangement, the link 6 connects the said levers to cause them to move in unison. The ends of one set of the toggle levers 5 are shown as fixed to a shaft 7 which has also fixed thereto an arm 8, the free end of which is in operative relation with a cam 9, said cam being arranged to rotate with a shaft 10. Driving means for the said shaft are provided of any suitable character and may be connected thereto in any desired or convenient manner. The said shaft is shown as having one or more gear wheels 11 which may be connected to the source of power.

Sheet conveying means for supplying sheets to the embossing couple and for removing them after impression are provided, said conveying means being constructed and arranged to move in a path intermediate the faces of the embossing members and also to move into substantially the same plane with the said members when they are at impression. In the embodiment of the sheet conveying means herewith illustrated the conveyer is shown adapted to co-act with guiding means which serve to guide the conveyer in its said path intermediate the faces of the embossing members, the said guiding means being movable with the movable embossing member as the embossing member moves to impression. The conveyer and the sheet which is held in position for impression between the embossing members move with the guiding means substantially into the plane of the faces of the embossing members when they are at impression. The sheet conveyer is herewith illustrated as

comprising flexible endless chains 12 carrying at suitable points thereon grippers 13. The guiding means for guiding the conveyer in its path intermediate the faces of the embossing members is shown as a frame 14 provided with suitable ways 15 in which the chains 12 of the conveyer travel. The frame 14 is shown mounted to slide upon the rods 4, and when the embossing members are out of impression, the said frame rests on the side frames 4^a and with the conveyer occupies a position intermediate the planes of the faces of the said embossing members. In the present embodiment the guiding means and conveyer are moved into the plane of the embossing faces when they are at impression by giving the said frame 14 a movement transversely to the faces of the said embossing couple along the rods 4. To effect this movement the movable embossing member 3 is shown provided with lugs 16 positioned to contact with the frame 14 during the movement of the member 3 toward impression. Adjusting means may be provided, if desired, so that the sheet carried by the conveyer in impression position may be brought accurately into the plane of the embossing faces during impression, and such adjusting means are herein shown as comprising set screws 17 carried by the said lugs 16.

Suitable mechanisms for supporting and moving the conveyer are provided and a form thereof is herewith illustrated. With these ends in view, the frame 14 is shown as having its transverse members in the form of rods or shafts 18 and 19 which serve as supports for sets of sprocket wheels 20 and 21 which engage the chains 12 of the conveyer. The upper stretches of the chains 12 are supported on pairs of sprockets 20^a, 21^a mounted on rods on shafts 18^a and 19^a. The sprocket wheels 21 are also utilized for the purpose of moving the conveyer along its path. Means are provided for imparting to the sprocket wheels 21 an intermittent rotary motion in one direction and as herein shown said means comprise a pinion 22 fixed to the shaft 19 and meshing with a pivoted geared sector 23. Means for oscillating the said sector 23 are provided and a form of such means is herein shown as comprising a link 24 pivotally connecting the sector to levers 25 fulcrumed on a rod 26, one of said levers carrying a friction roll 27 engaging a cam groove 28 in one of the gear wheels 11. Means are provided for causing the pinion 22 and sector 23 to intermesh as they come into engagement, and as herein shown the said means comprise a star wheel 29 carried upon the shaft 19 the points of which are adapted to register between a face 30 and pin 31 upon the sector 23.

The extent of the movement of the con-

veyer may be regulated and modified, if desired, and to effect this in the present embodiment, means are provided for changing the radial distance of the connecting point of the link 24 to the sector 23. The form of such means shown comprises a longitudinal slot 32 in the sector in which the pivoted pin 33 may be moved backward and forward and fixed at any point as desired. The link 24 is also shown as provided with a turn-buckle 34 which serves to change the relation of the sector 23 to the lever 25 and thus to alter or regulate the position of the conveyer grippers relatively to the embossing members. By means of the devices just described the movement of the conveyer may be adjusted and modified for sheets of varying sizes and for varying the position of the impression upon sheets of a particular size.

Means are provided for supplying sheets to the conveyer and the illustrated form of such means is designed for feeding sheets to the conveyer while the said embossing members are at impression. The chains 12 of the conveyer are shown as being connected at convenient intervals by cross bars 35 which, in addition to serving as alining means for the chains also constitute a part of the gripper mechanism. Pivoted adjacent to the said bars 35 are members 36 which are impelled by springs 37 to normally contact with the faces of the bars 35. Suitable means are provided for opening the grippers to receive a sheet, which may be fed thereto in any convenient manner. The illustrated form of gripper opening mechanism comprises a pin 38 adjustably mounted in a bracket 39 fixed to the embossing member 1, and so positioned that as the frame 14 moves upwardly with the movable embossing member 3 the free end of the member 36 contacts with the face 40 carried by the said pin, thus acting to open the gripper against its spring, and to hold it open until the member 3 begins to move away from impression. A feed table for the sheets is provided and is herein shown as fixed to the embossing member 3 and is designated by the reference numeral 41.

Means for registering the sheet are provided, said registering means being adapted to co-act with the conveyer and being also adapted to bring the conveyer and the sheet to position during the upward movement of the conveyer just as the embossing couple moves into impression. The said registering means is also shown as being provided with devices for bringing the conveyer and sheet positively and accurately into position just before the impression. In the illustrated embodiment, the registering mechanism is shown as comprising fingers 42 pivoted to a slide 42^a suitably guided on the fixed embossing member 1 and being yieldingly held in their engaging or opera-

tive position by suitable means such as 5 springs 43. This pivotal connection of the fingers 42 and the springs enables the said fingers which constitute the active part of the registering means to yield in a direction transverse to the direction of travel of the conveyer. The member 42 is provided with vertical edges and with a beveled end portion in order that as it moves into engagement with the gripper 13 or the chains 12 on which the gripper is mounted it will, by means of its beveled end, impart to said gripper or chain any slight movement necessary to bring the parts into operative relation. Means for positively moving the member 42 and the gripper engaged thereby into registering position are provided and a form of such means is herein shown as comprising connections between the said 15 member and the shaft 10. As illustrated, the connections for each member 42 include a link 44 connected to an arm 45 fixed to a shaft 46. Also fixed on the shaft 46 is an arm 47 connected by a link 48 to a bell 20 crank lever 49, the free end of said bell crank lever being in operative relation to a cam 50 carried upon the shaft 10. The said connections are held in operative relation by suitable means such as a spring 51 25 acting on an arm 52 fixed to the said shaft 46. By means of the said connections the member 42, through the actuation of the cam 50, is positively brought to registering position just prior to the impression. As 30 the members 42 operate to put the portion of the conveyer extending between said members and the feed table under tension, said portion of the conveyer being supported by the frame 14, the gripper 13 at 35 the feeding point will also be brought accurately to a predetermined or registering position so that the sheet may be accurately positioned therein. By reason of the vertical edges of the members 42 the grippers 40 will be accurately retained in their adjusted positions during the vertical movement of the conveyer caused by the movement of the embossing member 3 toward the member 1 to make the impression.

45 Suitable delivery means are provided, and according to many aspects of the invention the said delivery means may be of any desired character. As herein shown, the path of the conveyer after leaving the embossing 50 couple is inclined upwardly, and beneath the said upwardly inclined stretch is located an inclined receiving table 53 for the purpose of receiving the sheets as they are released by the conveyer. Suitably located 55 with reference to the said receiving table 53 are means for opening the grippers 13 so that the released sheet may fall upon the said table. As herein illustrated, the said gripper opening mechanism comprises 60 a cam 54 which is adapted to co-act with

the end of the pivoted member 36. The said member 54 is fixed on the stationary rod 19^a but may be shifted on the rod for the purpose of adjusting the amount of opening movement of the member 36. 70

The manner of operation of the mechanism hereinbefore described is as follows: A sheet being in position on the conveyer between the embossing members, the member 3 advances upwardly as the toggles 5 75 are actuated through the arm 8 and the cam 9. After the member 3 has advanced upwardly through a portion of its travel, the lugs 16 come in contact with the frame 14 which then moves forward with the member 3 toward impression carrying with it the conveyer and the sheet into the plane of impression. As the conveyer moves upwardly an idle gripper member 13 is in position with the free ends of the pivoted members 36 directly beneath the pins 38, which serve in the manner hereinbefore specified to oscillate the members 36 about their pivots and to open the gripper. A sheet is fed into the said gripper and as the member 3 recedes 80 from impression the pivoted members 36 close upon the sheet as the said members move away from the pins 38. The frame 14 recedes with the embossing member 3 during 85 a part of the travel of the latter and comes to rest on the side frames 4^a at an intermediate position with reference to the positions of the embossing members when 90 away from impression. This guide frame 14 thus serves as means for separating the 95 sheet conveying means and embossing members transversely to the planes of the latter after impression, the side frames 4^a serving as means for separating the guide member and the movable embossing member during 100 the latter part of the downward movement 105 of the latter. As the frame 14 moves downwardly the pinion 22, which passed out of engagement with the sector 23 as the member 3 moved to impression, approaches the 110 sector 23, the star wheel 29 co-acting with the face 30 and the pin 31 serving to cause the pinion and sector to intermesh. The sector is then oscillated about its pivot by 115 its actuating mechanism, including the lever 25 and the cam groove 28, to rotate the pinion which through the medium of the sprockets 21 give a forward feed to the conveyer and the impressed sheet is fed forward over the delivery mechanism, and is 120 released from its gripper by the cam 54 and drops upon the receiving table 53. The sheet on the feed table 41 held by the grippers is moved forward into position between the embossing members. It will be 125 understood that the sector oscillates in the reverse direction while out of mesh with the pinion 22. As the member 3 advances to impression, as above described, the gripper 13 comes into contact with the beveled 130

end of the registering members 42 and by the action of the beveled end and the upward movement of the conveyer, the conveyer and registering members are brought 5 into proper operative relation. The conveyer is then given a supplementary movement so that the grippers at both the embossing position and the feeding position are positively brought to position by means 10 of the action of its cam 50 upon the lever 49 and the intermediate connections of the member 42.

From the foregoing it will be understood 15 that a press has been provided having sheet handling means adapted to take a sheet at a point near the embossing couple and during the impression when the grippers and feed table are at rest; which are adapted 20 to carry the sheets between the members of the embossing couple in a path which is clear of the face of both embossing members, thus obviating any danger of interference of those parts with each other and consequent damage to the dies or the 25 conveyer. The recession of the conveyer from the face of each of the dies before the outward feed of the sheet also effects the removal of the sheet in a direction obliquely to the die faces in case the sheet has stuck 30 to either face during the impression, thus preventing destruction of the sheet or delay to the press from having the sheet adhere 35 to the surfaces of the die. The registering means being adapted to co-act with the conveyer and having a positive actuating means permits of accurate and exact positioning 40 of the sheet without danger of defacement thereof, and the yielding action against its spring precludes any injury to either the 45 registering device or the conveyer in case they come into contact improperly. The delivery devices provided are also of a simple and compact structure and of certain action.

50 Other objects and advantages, in addition to those herein specified are realized by the invention.

The invention, in its broader aspects, is not limited to the particular constructions 55 shown, nor to any particular constructions by which it has been or may be carried into effect, as many changes may be made in the construction without departing from the main principles of the invention and without sacrificing its chief advantages.

What I do claim as my invention and desire to secure by Letters Patent, is:

1. An embossing press including in combination, a pair of flat embossing members, 60 means for effecting a relative movement of said members to and away from impression, means for conveying sheets between said members, and means for effecting a movement of said conveying means transversely 65 with relation to the plane of each of said

members after impression, to separate the sheets from both said members.

2. An embossing press including in combination, a pair of flat embossing members, 70 means for effecting a relative movement of said members to and away from impression, and means for conveying sheets between said embossing members, said sheet conveying means being constructed and arranged to move in a path intermediate the faces of 75 said respective embossing members and also to move into substantially the same plane with said embossing members when they are at impression, and means for separating said sheet conveying means and said embossing members transversely to the planes of the latter after impression.

3. An embossing press including in combination, a pair of flat embossing members, 80 means for effecting a relative movement of said members to and away from impression, a sheet conveyer, means for moving said sheet conveyer in a path intermediate the faces of said embossing members to supply a sheet thereto prior to impression and for 85 removing the sheet after impression, and means for moving said sheet conveyer so as to bring the sheet substantially into the plane of the embossing members during the impression and for restoring it to a position intermediate the said faces after they 90 have moved away from impression.

4. An embossing press including in combination, a pair of embossing members, 100 means for effecting a relative movement of said members into and away from impression, a sheet conveyer, means for guiding the said conveyer in a path intermediate the faces of the embossing members when they are away from impression, means for causing 105 said guiding means to move with one of the embossing members when the said embossing member moves to impression, and means for separating said guiding means and said last mentioned embossing member 110 when the latter moves away from impression.

5. An embossing press including in combination, a pair of flat embossing members, 115 means for effecting a relative movement of said members, means for conveying sheets between said members, and means rendered operative by said first mentioned means for effecting a movement of said conveying means other than its conveying movement and transversely with relation to the plane 120 of each of said members when the latter are moved to and from impression.

6. An embossing press including in combination, a stationary embossing member, a movable embossing member, a sheet conveyer, a member adapted to guide the conveyer intermediately between the faces of the embossing members when away from impression, means for causing the guiding member to move with the movable emboss- 130

- ing member to impression, and means for separating the guiding member and the movable embossing member after impression.
7. An embossing press including in combination, a stationary embossing member, a movable embossing member, a sheet conveyer, a member for guiding said conveyer in a path intermediate and substantially parallel to the faces of the embossing members when away from impression, guides for said guiding member, connections between the guiding member and the movable embossing member so that the guiding member, the conveyer and the said embossing member will move to impression together, and means for separating the guiding member and the movable embossing member after impression.
8. An embossing press including in combination, a stationary embossing member, a movable embossing member, a flexible endless sheet conveyer, a member adapted to guide the conveyer intermediately between the faces of the embossing members when away from impression, means for causing the guiding member to move with the movable embossing member to impression, and means for causing the movable impression member to move independently of the guiding member after impression.
9. An embossing press including in combination, a stationary embossing member, a movable embossing member, a flexible endless sheet conveyer, a member for said conveyer constructed and arranged to guide said conveyer to move in a path intermediate and substantially parallel to the faces of the embossing members when away from impression, guides for said guiding member, and connections between the guiding member and the movable embossing member so that they will move to impression together and will be separated after impression.
10. An embossing press including in combination, a stationary embossing member, a movable embossing member, means for moving said member to and away from impression, a flexible endless sheet conveyer, a guide member for said conveyer located intermediately of said embossing members, guides for said guide member, connections between said guide member and said movable embossing member for causing them to move to impression together, means for separating said members after impression, and means for moving said conveyer relatively to its guiding member when away from impression.
11. An embossing press including in combination, a pair of flat embossing members, an endless conveyer having a plurality of sheet gripping means for receiving sheets and conveying them between the said embossing members, intermittently operating actuating means for the sheet conveyer, and means acting on the conveyer adjacent to the gripping means located at the embossing position for giving the conveyer a supplemental movement in the forward direction to accurately position said sheet gripping means at both the receiving and embossing positions.
12. An embossing press including in combination, a pair of flat embossing members, an endless sheet conveyer provided with grippers for receiving sheets and conveying them between said embossing members, intermittently operating actuating means for the conveyer, means acting on the conveyer adjacent to the grippers located at the embossing position for giving the grippers a supplemental movement to accurately position them at both the receiving and embossing positions.
13. An embossing press including in combination, a pair of flat embossing members, an endless conveyer having a plurality of grippers for receiving sheets and conveying them between the said embossing members, intermittently operating actuating means for the sheet conveyer, and means acting upon the conveyer adjacent to the grippers located at the embossing position for giving the conveyer a supplementary movement prior to impression and holding it in a predetermined position during impression to accurately position the grippers at both the receiving and embossing positions.
14. An embossing press including in combination, an embossing couple, a conveyer for feeding sheets to said couple, and means constructed and arranged to engage the conveyer by a relative movement transverse to its direction of travel and move it to register the sheet for the impression, said registering means being constructed and arranged to yield in a direction transverse to the direction of the travel of the conveyer.
15. An embossing press including in combination, an embossing couple, a conveyer for feeding sheets to said couple, means constructed and arranged to engage the conveyer by a relative movement transverse to its direction of travel and move it to register the sheet for the impression, said registering means being constructed and arranged to yield in a direction transverse to the direction of the travel of the conveyer, and means for positively actuating the registering means.
16. An embossing press including in combination, an embossing couple, the members of which are relatively movable, a sheet conveyer movable with one of said members, yielding movable registering means carried by the other of said members for co-acting with the sheet conveyer to register the sheet for the impression, and means for positively actuating said registering means.

- 6
17. An embossing press including in combination, a pair of flat embossing members, a traveling sheet conveyer, a pivoted spring pressed registering finger adapted to engage said conveyer, and means for positively actuating said finger to move said conveyer when a sheet is to be registered.
18. An embossing press including in combination, an embossing couple, the members of which are relatively movable, a sheet conveyer movable with one of said members, and registering means carried by the other of said members for moving the sheet conveyer to register the sheet for the impression.
19. An embossing press including in combination, a pair of flat embossing members, a flexible conveyer for carrying sheets between the said members, a movable guide member on which said conveyer is carried, driving means for said flexible conveyer including a pinion mounted on said guide member, an oscillating gear sector adapted to mesh with said pinion when it moves in one direction, and means for moving said guide to move said pinion out of mesh with the said sector when it moves in the opposite direction.
20. An embossing press including in combination, a pair of flat embossing members, a flexible conveyer for carrying sheets between the said members, driving means for said flexible conveyer including a pinion, an oscillating gear sector for driving said pinion, means for causing the said pinion and sector to be in engagement when the sector moves in one direction and to pass out of engagement when the sector moves in the other direction, and means for causing them to intermesh when they pass into engagement.
21. An embossing press including in combination, a pair of flat embossing members, an endless conveyer for carrying sheets between said members, driving means for said conveyer including a pinion, an oscillating sector meshing with said pinion during the stroke of the sector in one direction, means for separating the sector and pinion during the stroke of the sector in the opposite direction, and actuating means for said sector.
22. An embossing press including in combination, a fixed embossing member, a movable embossing member, a sheet conveyer, guiding means for said sheet conveyer adapted to position the said conveyer intermediately of the faces of the said embossing members when they are away from impression to separate the sheets from both said members, means for carrying the said guiding means and the conveyer toward impression with the said movable embossing member, a feed table fixed with reference to said movable embossing member, a gripper upon said conveyer, and means for opening said gripper during the impression so that a sheet may be fed thereto from the said feed table.
23. An embossing press including in combination, a fixed embossing member, a movable embossing member, a sheet conveyer, guiding means for said sheet conveyer adapted to position the said conveyer intermediately of the faces of the said embossing members when they are away from impression to separate the sheets from both said embossing members, means for carrying the said guiding means and the conveyer toward impression with the said movable embossing member, a feed table fixed with reference to said movable embossing member, a gripper upon said conveyer, and means carried by said fixed embossing member for opening the said gripper.
24. An embossing press including in combination, a fixed embossing member, a movable embossing member, a sheet conveyer, guiding means for said sheet conveyer adapted to position the said conveyer intermediately of the faces of the said embossing members when they are away from impression to separate the sheets from both said embossing members, means for carrying the said guide and the conveyer toward impression with the said movable embossing member, a gripper upon said conveyer, an inclined receiving table, and means for automatically opening the gripper when the sheet carried thereby is above the table.
25. An embossing press including in combination, a supporting frame, a fixed embossing member carried thereon, a flexible endless conveyer, guiding means for said conveyer movable upon said frame and constructed and adapted to guide said conveyer in a path intermediate the faces of said embossing members when away from impression, means for causing said guiding means to move with the said movable embossing member as it goes to impression, a feed table fixed to said movable embossing member, a gripper upon the said conveyer, means for holding the gripper open during the impression, and means for moving said conveyer along its path of travel when said embossing members are away from impression.
26. An embossing press including in combination, a supporting frame, a fixed embossing member carried thereon, a flexible endless conveyer, guiding means for said conveyer movable upon said frame and constructed and adapted to guide said conveyer in a path intermediate the faces of said embossing members when away from impression, means for causing said guiding means to move with the said movable embossing member as it goes to impression, a feed table fixed to said movable embossing member, a gripper upon the said conveyer, means for holding the gripper open during the impression.

sion, means for moving said conveyer along its path of travel when said embossing members are away from impression contact, an inclined receiving table, and means for automatically opening the gripper when the sheet carried thereby is above the receiving table.

In testimony whereof, I have signed my name to this specification, in the presence of two subscribing witnesses,

ALFRED BREDENBERG.
